Patent Agency.

UNITED STATES PATENT OFFICE.

J. S. PECKHAM AND M. PECKHAM, OF UTICA, NEW YORK.

DESIGN FOR A STOVE.

Specification forming part of Design No. 89, dated October 3, 1846.

To all whom it may concern:

Be it known that we, JOHN S. PECKHAM and MERRITT PECKHAM, of Utica, in the county of Oneida and State of New York, have invented or produced a new Design for a Parlor-Stove; and we do hereby declare that the following is a full, clear, and exact description of the same, reference being had to the accompanying drawings, making part of this specification, in which—

Figure 1 is a front elevation, and Fig. 2 a side elevation, thereof.

The same letters indicate like parts in all the figures.

This stove is an ornamental Gothic structure, consisting of a base, A, which is the fire-box, resting on a broad hearth, B, and supported on four legs, C, with Gothic ornaments. On this base rest two square columns, D, which are jointed at the top by an entablature, E, of ornamental pattern. Said columns and the entablatures form the smoke-pipe, which is connected at the back with the funnel. (Not shown in the drawings.) In front there is a double door, a, on each half of which there are two lancet-headed panels, alternated with tower-pilasters b. Between the two doors there is a heavy ornamented molding, c, enlarged in the middle and tapering up and down. On each side of the doors there is a lancet-headed panel, d, including a tower ornament. The legs show three faces of a prism, with moldings at top and bottom, on each face of which are Gothic panels, and below they terminate in a scroll ornament, e, below the molding at the top of the base, and above the doors there is a row of brackets, f, each of which has a quarterfoil ornament in the die and an ogee ter-

mination below. These brackets extend around the ends, below which there is a Gothic panel, which on one end forms the door g, in the center of which there is a casket-shaped ornament. On each of the columns in front there is a quarterfoil molding at the base inclosing a bow or knot. Above this there is a double-headed lancet-shaped panel, with an ogee molding terminating in a finale above, a quarterfoil being placed in the tracery. A Gothic spire, with a door and window surmounting it, is placed in this panel and highly ornamented. On the capitals there are three foliated ornaments, and each of them is surmounted with an ornamented cupola-formed pinnacle. The entablature or panel, which is sunk below the capitals of the columns, has a castellated ogee-formed molding at top, terminated by a large and expanded finale, and below there is a row of pendants, three in number, with two semi-pendants connected with the columns. There is a tracery molding on the face of this entablature, with a temple-formed ornament in the center flanked by two lancet-headed recesses or moldings. The sides of the columns have the quarterfoil below surrounded by beading and a panel within a recess above, also surrounded by a beading. It terminates similar to the front.

Having thus fully described and represented our design, we desire to secure the same by Letters Patent, as herein set forth.

JOHN S. PECKHAM.
MERRITT PECKHAM.
